UNITED STATES PATENT OFFICE.

EMIL FISCHER, OF NEW YORK, N. Y.

UPPER FOR SHOES.

1,289,720.

Specification of Letters Patent. Patented Dec. 31, 1918.

Application filed April 7, 1917. Serial No. 160,528.

To all whom it may concern:

Be it known that I, EMIL FISCHER, a subject of the King of Hungary, residing at New York city, in the county of New York 5 and State of New York, have invented new and useful Improvements in Uppers for Shoes, of which the following is a specification.

This invention relates to shoes, more particularly to an improvement in the art of producing uppers for shoes; and the main objects of the same are:—to produce complete uppers for shoes out of single pieces or blanks of material; to produce in a similar manner uppers for shoes which are neat and attractive in appearance, and which are comfortable and durable in service; to provide in a similar manner uppers for shoes having parts so arranged that the work of assembly is reduced to a minimum, and may be performed successfully by those who have had but little training in the trade of shoe making.

With these objects and others in view, my invention consists in the details of construction, and in the arrangement and combination of parts hereinafter more fully set forth and claimed.

In the drawings, Figure 1 is a view in perspective of a shoe embodying my improved uppers. Fig. 2 is a plan view of my improved uppers for shoes, the view representing the same as they appear when cut from a single piece or blank of material.

I am aware that hitherto uppers for shoes have been produced or cut from a single piece or blank of material, but the methods of producing the same, due to the cut or pattern of the various parts, entails considerable work and skill in their proper assembly; and frequently, also, in order that the shoes produced therefrom may be maintained comfortably upon the foot of the wearer, additional parts, straps or lugs must be added by sewing, riveting or otherwise securing them to the main body of the uppers. I have, therefore, conceived the idea of so cutting or producing the complete uppers from a single piece of material that no additional parts, straps or lugs need to be added in order to produce comfortable enduring uppers, except the usual fastening means such as buckles, buttons, or the like.

With more particular reference to the accompanying drawings, I take a single piece of material such as prepared leather,

prepared canvas, or other material suitable for the purpose and cut therefrom by hand or machine, a form of uppers comprising a toe portion 5 which merges into confronting side portions 6 and 7.

The outer ends or edges of the said portions 5, 6 and 7 may be of any desirable form or configuration in accordance with the size, type or style of shoe which is to be produced. The toe portion 5 is provided on its inner end or edge with a tongue 8 which may be of any desirable length, and which near the top end thereof is provided with parallel cuts or slits 9 for a purpose to be hereinafter described.

The side portion 6 is formed on its inner edge with the straps 10 and 11, which are spaced-apart in accordance with the height of the shoe for which they are to be employed, the said strap 11 being considerably longer than the said strap 10, because it is required to extend across a higher portion of the instep or ankle. The side 7 is also formed on its inner edge with the flaps or lugs 12 and 13. These flaps are formed in a position approximately opposite the respective points to which the straps 10 and 11 are formed with the side 6. The toe portion 5, as well as the side portions 6 and 7, may be formed with any suitable arrangement or configuration of eyes as 14, or other embellishing designs, which may add to the appearance of the uppers.

In the uppers, thus cut out, it will be observed that the inner edges of the side portions 6 and 7 converge generally from the inner edge of the toe portion to the remote edges or heels 15 and 16, respectively, although the spaces 17 and 18, located, respectively, between the tongue portion 8 and the strap 10, and between the latter and the strap 11 approach approximately more nearly to the outer edge of the side portion, in order to compensate suitably and comfortably for the enlarged portion of the foot. Also, it will be observed that the inner converging edges of the side portions 6 and 7 at the rear of strap 11 and flap 13, serve to provide rearwardly widening side portions, which, when united by sewing or otherwise at the rear ends 15 and 16, comprise the heel portion of the uppers for encompassing the heel of the wearer as shown in Fig. 1.

When the uppers have thus been cut out from a single piece of material, the same are

placed upon an appropriate last and the sole 19 and heel 20, as shown in Fig. 1, secured thereto, by sewing, riveting, or in any suitable manner known to the trade. To each of the flap portions 12 and 13 is secured a buckle as 21, the tongue 22 of which is adapted to be engaged in a choice of apertures as 23 to enable the wearer to fasten and adjust the shoe upon his foot by the manipulation of the buckle in the usual manner. Before, however, securing the strap 11 to its buckle, it is first passed through the slots or slits 9, on the top end of the tongue 8, whereby to secure said tongue and said strap in proper relative position upon the instep of the wearer; it being also noted in this connection that the strap 10, before being secured to its buckle, is extended across the top of the tongue 8.

Having thus described my invention, what I claim is:—

1. As an article of manufacture, an upper for a shoe formed from a single piece of material and comprising a toe portion 5 which merges into relative widening confronting side portions 6 and 7, and into an inner tongue portion 8 extending therebetween, the said side portion 6 being provided with two differently formed spaced-apart inwardly projecting straps 10 and 11,

and the said side portion 7 being provided with spaced-apart inwardly projecting flaps 12 and 13.

2. As an article of manufacture, an upper for a shoe comprising a toe portion 35 merging into confronting side portions, the said toe portion being formed on its inner edge with an integral projecting tongue having an eye near its top end, one of said side portions being formed with integral 40 spaced-apart straps, the strap more remote from the toe portion being longer than the nearer strap, the other side portion being formed with integral spaced-apart flaps in positions to correspond approximately with 45 the positions of said straps, and means adapted for detachably securing and adjusting each strap to each flap, the nearest strap being adapted to be secured in a position overlying said tongue, and the more remote strap being adapted to be passed through the eye of said tongue before securing to its flap, the inner edges of the side portions suitably converging toward their rear ends in order to provide widening material for encompassing the heel of 50 the wearer.

In testimony whereof I have signed my name to this specification.

EMIL FISCHER.
